Application October 17, 1955, Serial No. 540,879

16 Claims. (Cl. 248—263)

This invention relates to fixtures or brackets for curtain and drape bars, rods and the like, and particularly to fixtures which can be utilized in mounting a large number of different types of brackets, including conventional brackets, as well as certain novel brackets constructed in accordance with this invention.

There are numerous types of brackets and fixtures which may be utilized in mounting curtains, drapes and the like, such as across or at each side of a window. Normally, such brackets are mounted or affixed to a window frame or the wall alongside the window frame by screws, nails or the like. Due to the variety of types of brackets, whenever the type of bracket is to be changed, due to the fact that each time a different type of bracket is to be installed, the old bracket must be removed and the new bracket placed in position, as well as due further to the fact that more often than not the attachment holes of the new bracket will not be accommodated by the holes for the old screws or the like, particularly in apartment houses or in rented premises, the walls and window frames often become severely damaged by the number of holes made therein. Also, when one tenant is moving out and another tenant is moving in, it is often necessary for the owner to have the wall or window frame repaired, so that the new tenant may make his own holes (to be left in the wall for repair when he leaves). Also, some persons prefer merely window curtains and side drapes, others prefer various types of blinds and drapes, while others prefer merely curtains or drapes as a window covering, while some persons may prefer that the drapes or curtains extend to a different position laterally than other persons prefer. Normally, each type of curtain or drape to be installed requires a different type of bar or rod for mounting the same, with a resultant difference in the mounting bracket.

Since the repair of damage to walls, window frames and the like constitutes an item of considerable expense, such expense could be saved in the event that a fixture were available which could be relatively permanently mounted on walls or window frames and the like and would be adapted to receive and hold in position almost any conventional type of bracket, irrespective of whether curtains, drapes or other types of window coverings or decorative elements would be utilized and also irrespective of the lateral positioning of the same. Thus, it is an object of the present invention to provide a fixture which may be attached to a wall, window frame or the like, so that any conventional type of mounting bracket for curtains, drapes and the like can be removably attached thereto, but which may readily be removed and others substituted without the necessity of attachment of the conventional bracket to the wall, window frame or the like.

Additional objects of the invention are to provide such a fixture which is adapted to receive and hold in a firm and solid position a large number of such conventional mounting brackets or the like; to provide a novel auxiliary element for such a fixture which enables stationary rods, as well as swinging rods, to be supported; to provide a

2

further auxiliary element which in conjunction with such a fixture enables a large number of conventional brackets or the like to be supported at a position laterally of the relatively permanent fixture; to provide such a fixture and

5 novel auxiliary elements which are relatively simple in construction and therefore may be made at a moderate cost, but which are sufficiently strong to withstand the rigors of hard usage.

Additional objects of this invention and the novel features thereof will become apparent from the description which follows, taken in connection with the accompanying drawings, in which:

Fig. 1 is a perspective view, on a reduced scale, of a window, on each side of which a curtain rod or bar is supported by a conventional bracket mounted in a fixture constructed in accordance with the present invention;

Fig. 2 is a front elevation of one of the fixtures of this invention of Fig. 1;

Fig. 3 is a vertical section, taken along line 3—3 of 20 Fig. 2;

Figs. 4 and 5 are similar perspective views of the fixture of Fig. 2, but with different types of conventional curtain or drape bar brackets mounted thereon;

Fig. 6 is a perspective view of the fixture of Fig. 2, 25 with a further type of curtain or drape bracket holder mounted thereon;

Fig. 7 is a perspective view of the fixture of Fig. 2 and an auxiliary element, also constructed in accordance with this invention and particularly adapted to receive a 30 rod for a drape or the like, or a swinging rod for a drape or a curtain;

Fig. 8 is a side elevation of the fixture of Fig. 2 and a further auxiliary element, also constructed in accordance with this invention and adapted to permit the mounting of a conventional bracket for a curtain or drape rod or bracket laterally of the position of the fixture in Fig. 1;

Fig. 9 is a vertical section, taken along line 9—9 of 35 Fig. 8;

Fig. 10 is a vertical section, taken along line 10—10 of Fig. 8;

Fig. 11 is a vertical section similar to Fig. 10, illustrating an alternative construction; and

Fig. 12 is a vertical section illustrating a structural 45 modification and taken at the position of line 12—12 of Fig. 8.

As illustrated in Fig. 1, a fixture F may be installed at one side and a fixture F' at the other side of a window 10, the fixtures F and F' being similar in construction but

50 complementary so that one is left hand and the other right hand. The fixtures F and F' may be secured to the frame of window 10 or to the wall at each side of the window frame and are also adapted to be left in position, so that from this standpoint they may be considered as relatively permanent. As shown, a curtain bar 11 extends between the fixtures F and F', the same being of a conventional construction having rounded upper and lower flanges and conveniently comprising two sections, one being adapted to slide into the other so that the length

55 of the bar may be adjusted. The opposite ends of bar 11, normally extending at right angles to the remainder of the bar, are not attached directly to the fixtures F and F', but rather to a conventional bracket B, shown more clearly in Figs. 2 and 3, and comprising a base 12 which

60 is normally attached to the window frame or wall by screws, nails or the like passing through suitable holes therein, but when utilized in conjunction with the fixtures F or F', is merely clamped thereto. A pair of prongs 13 extend forwardly in spaced relation from opposite edges 65 of the base 12 and each prong is provided with a hook 14 at its upper end adapted to engage a suitably formed hole in the upper rounded flange of the bar 11, as in Fig. 3,

while each prong also has a rounded lower edge 15, over which the lower rounded flange of bar 11 is adapted to snap, to hold the bar in position on the bracket. Other forms of brackets, which may be attached to the fixture F in the same relative position as the bracket B of Figs. 1 and 2, include a bracket B₁ of Fig. 4, having a similar base 12 but a single prong 13, as well as a bracket B₂ of Fig. 5, having a similar generally rectangular base 12' and a prong 16 in which a spring clip 17 is formed, as by stamping, so as to hold the inwardly extending ends of a bar similar to bar 11, with the upper and lower rounded flanges in engagement with the correspondingly curved edges 18 of prong 16, formed by relatively short, longitudinal flanges bent over in an arc. The bracket B of Figs. 2 and 3 is particularly adapted to be utilized for the installation of a pair of bars 11 which are adapted to hold center curtains and side curtains or drapes, while each of the brackets B₁ and B₂ is adapted to hold only a single bar.

As indicated previously, the fixtures F and F' are similar but complementary in construction and each may comprise a rear plate 20 which may be slightly thinner than a front plate 21, the rear plate 20 conveniently being left flat and stamped out to a rectangular shape with rounded corners, while front plate 21 may be stamped to shape and additional stamping or similar operations performed thereon to provide a forwardly offset portion 22 generally parallel to the rear plate 20 and adapted with rear plate 20 to form a vertically extending socket 23 having a width preferably considerably greater than its thickness and adapted to receive a flat bar or flange of an auxiliary element, such as described later. The forwardly offset portion 22 is preferably formed generally centrally of the front plate 21, while adjacent one edge and at the top, a portion of the front plate is bent over and downwardly to form a flange 24 which extends downwardly in generally parallel relation to the front surface of plate 21. The inner edge of flange 24 may be adjacent the offset portion 22, so that the latter will tend to limit inward movement of the base 12 of bracket B when received beneath flange 24, as in Fig. 2. The bottom of base 12 of bracket B or B₁ or base 12' of bracket B₂, may be anchored by any suitable clamping means, preferably adjustable, such as a clamp C having an upper flange 25 adapted to press against the base of the bracket B, B₁ or B₂, and a slot 26 by which the position of clamp C may be adjusted to accommodate different lengths of base of the brackets or the like to be installed therein, as well as to facilitate placement of the bracket in position and tightening of the clamp thereagainst. The clamp C may be tightened in any suitable manner, as by a set screw 27 which extends through slot 26 and into a threaded hole provided for the purpose in the plates 20 and 21, as in Fig. 3. The plates 20 and 21 also may be secured together in any suitable manner, as by spot welds 30 placed adjacent opposite sides of the plates, while plates 20 and 21 may be further provided with holes 31 extending through both plates, conveniently adjacent the edges of the plates opposite the position of flange 23 and clamp C. The longitudinal or vertical distance between holes 31 is preferably sufficient that when fixture F or F' is attached to a wall, window frame or the like, as by a screw or other suitable type of attaching device extending through each hole 31, the fixture will be able to withstand any normal load or twisting stress placed thereon. Due to the fact that the fixtures F and F' remain attached substantially permanently, there is less tendency for the screws or other fastening devices to become loose.

The fixture F' may comprise parts identical to those of the fixture F except, as indicated above, the parts are complementary, i.e., the holes 31 and the flanges 23 and the clamp C will be on the sides opposite those for fixture F. Preferably, the fixtures F and F' are installed so that the flange 23 and clamp C are on the outside, i.e., away

from the window, so that bar 11 or other suitable device for supporting curtains, drapes or the like, will extend to or past the fixtures. Thus, the curtains or drapes will tend to hide the fixtures F and F' from view. However, fixtures F and F' may, if desired, be installed in a position reverse to that described above.

Other types of brackets or curtain or rod supports may be mounted on the fixtures F and F', such as a bracket B₃ of Fig. 6, which includes a forwardly extending arm 33 having side flanges 36 to add additional strength and one or more slots 37 and 37' by which a curtain or drape rod or bracket may be attached, as by a suitable clamping screw extending through slot 37 or 37'. The arm 33 extends forwardly from a base 38, the upper end of which extends beneath the flange 24 of the fixture F or F' and the lower end of which is clamped by flange 25 of the clamp C against the plate 21. It will be noted that the bracket B₃ may be constructed so that the rear ends of the side flanges 36 extend alongside the fixture flange 24, thus adding to the stability of the attachment. The bracket B₃ may be formed from one or more pieces of metal, as from one piece by stamping out to a suitable shape, so that a rearwardly extending portion may be bent downwardly to form the portion of base 38 beneath arm 33 and the upper portion of base 38 may be formed by flanges bent inwardly from sides 36, stamped so as to extend rearwardly before being turned inwardly to provide such flanges. Normally, of course, bracket B₃ will, as in the case of the brackets B, B₁ and B₂, have holes therein for attachment by screws or the like to a wall, window frame or the like, but such holes will not be necessary for use with the fixtures F and F', although if present in conventional brackets they may remain, since they neither add to nor detract from the ability of the fixtures F and F' to hold the brackets in position.

Normally, a bar of the general type exemplified by bar 11 and brackets of the type exemplified by brackets B, B₁, B₂ and B₃ are utilized in supporting curtains or drapes having a relatively light weight, since for heavier curtains or drapes, a stronger support may be desired. Thus, a steel rod is often mounted between brackets for supporting a heavier curtain or drapes, while side drapes are often pivoted so that they may be swung inwardly toward or outwardly from the window. For supporting such a rod or rods, an auxiliary element, such as a rod support R of Fig. 7, may be utilized in conjunction with each of the fixtures F and F'. Each rod support R may be made from flat strip having a rear flange 40 adapted to be placed in the socket 23 of the respective fixture and a forwardly extending arm 41 at the front end of which a well is formed by vertical flanges 42 and 43 on opposite sides of a downwardly offset, horizontal flange 44, it being evident that a rod, having either a round or any other cross sectional shape and also either solid or hollow, as well as single or multiple for adjustment of length, may be placed in this well. Thus, each end of the rod will be supported forwardly of the window at the position of each of the fixtures F and F', so that a heavier curtain or drape may be placed on such a rod. In addition, the outer end of rod support R may be formed to provide an open sided, box-shaped structure having a top 45, a bottom 46 and a front 47, the rear of the box being formed by flange 43. The top 45 and bottom 46 of the box may be provided with aligned holes for insertion of the right angularly disposed end 48 of a curtain or drape rod 49, conveniently having an adjustable tubular extension 50. As will be evident, rod 49 may be swung around to any desired position with the end 48 thereof pivoting in the holes provided therefor in the rod support R. The rod support R is preferably made of sufficiently thick material that a relatively heavy drape may be supported at or adjacent its outer end, although with a reasonable width the rod support need not be unduly thick.

The rod support R may be made from a single piece

of material, normally metal, as by stamping. As will be evident, the holes in box top 45 and bottom 46 may be punched in the metal, following which the box bottom 46 may be bent to a perpendicular to box side 47 and the latter then bent to a perpendicular to flange 43, which may then be bent to a perpendicular to horizontal flange 44 and flange 42 then formed. Rear flange 40 may be formed at any suitable time, as either the first or last or an intermediate operation, as well as simultaneously with another operation. It will be understood, of course, that variations in the above operations may be utilized, that the corners between the various flanges and the box parts need not be sharp but may be rounded, as may be the bottom of the well, and that the rod support R may be formed of two or more pieces welded or attached together in any suitable manner. The parts of the fixtures F and F' and also rod support R may be made of steel or other suitable material, chrome plated or otherwise treated to produce a desirable finish. Of course, the fixtures F and F' and/or rod support R may be enameled or painted, or otherwise surface treated to provide various colors, as well as desired configurations or designs thereon.

When the drapes, curtains or the like are to extend laterally to positions farther from the window than the comparatively fixed position of the fixtures F and F', it is unnecessary to shift the position of the fixtures F and F' in the event that a lateral support L, as illustrated in Figs. 8-10, is available. Each lateral support L may include a bar 55 conveniently formed of strip material and provided at one end with a depending flange 56, which also may be made of strip material, with the inner end 57 of the former offset and spot welded, as at 30', or secured in any other suitable manner to the upper end of flange 56, it being noted that the flange 56 preferably lies in substantially the same plane as the bar 55, so that the flange 56 may be placed in the socket 23 formed between the forwardly offset portion 22 of the front bracket 21 and the rear plate 20 of a fitting F or F'. Due to the greater width than thickness of the socket 23, the lateral support L does not tend to twist. Thus, an auxiliary fixture F'', which may be similar to the fixture F or F', but need not be provided with holes for attachment by screws or the like to a wall or window frame, may be mounted on the front side of bar 55, as by spot welding the latter to rear plate 20, as in Fig. 10, or, as in Fig. 11, the rear plate 20' may extend only up to the bar 55, so that the bar 55 may be spot welded or otherwise suitably attached directly to the front plate 21' and the portion of bar 55 opposite the offset portion 22 of front plate 21' may form a corresponding part of the rear wall of the socket 23, as in Fig. 11. Front plate 21' and rear plate 20' are also conveniently attached together in a similar manner, as before, such as by spot welds 30. Also, front plate 21', in addition to offset portion 22, is provided with an upper flange 25 at its outer edge, and a clamp C may be provided in the manner previously described. As will be evident, any desired type of bracket may be attached to fixture F'', or an auxiliary fixture such as rod support R, in the manner previously described. Also, if desired, the auxiliary fixture F'' may be removably attached to bar 55, as by screws, bolts or the like, and also may be adjustable therealong. Bar 55 also may be provided with longitudinal flanges or one or more longitudinal ribs, such as rib 57 of Fig. 12, which may taper in width and depth from adjacent one end of bar 55 to adjacent the opposite end, to increase the strength thereof as a beam supported at one end.

From the foregoing, it will be evident that the fixtures constructed in accordance with this invention, as well as the auxiliary elements, fulfill to a marked degree the requirements and objects hereinbefore set forth. It will be understood that various changes in the construction thereof may be made, in addition to those indicated.

Also, other embodiments of this invention may exist, without departing from the spirit and scope thereof.

What is claimed is:

1. A fixture for curtain and drape bars, rods and the like, said fixture and complementary fixture being adapted to be installed at opposite sides of a window or the like, comprising a front plate and a rear plate attached together in overlying relation by spot welds adjacent the longitudinal edges thereof, said front plate having a forwardly offset portion extending from top to bottom thereof in a central position so that said plates form, in upright position, an upright socket for receiving a bar-like member; said front plate also being provided with a flange at the upper end and at one side of said forwardly offset portion, said flange extending outwardly and then downwardly in spaced, generally parallel relation to said front plate; said plates having longitudinally spaced holes therethrough adjacent the edge opposite said flange for attachment to a wall or the like by screws or the like; a clamp having a longitudinal slot therein and an upper, upwardly extending flange disposed in opposed relation to said plate flange; and a screw extending through said slot and said plates for adjustably attaching said clamp to said plates, said plates having a threaded hole therein for receiving said screw.
2. For use with a fixture as defined in claim 1, an auxiliary element comprising an arm adapted to extend horizontally from said fixture and having a rear flange extending downwardly into said fixture socket; said arm being formed from flat stock and provided with a well for receiving a bar, rod or the like, said well having an open top, a horizontal bottom and generally vertical front and rear sides; said arm having at its outer end a box formed by said front side of said well, a horizontal top, a generally vertical end and a horizontal bottom extending back to said well, said box bottom and top being provided with aligned holes for receiving an angular end of a generally horizontal rod which is thereby swingable about said arm box, said well and said box being formed from a continuous strip from which said arm is formed.
3. For use with a fixture as defined in claim 1, an auxiliary element comprising a bar adapted to extend laterally from the upper edge of said fixture, said bar having an offset inner end spot welded to a flange bar extending downwardly in said fixture socket and the outer end of said bar being attached to a second fixture including front and rear plates with said front plate having a longitudinal offset portion in the center and a downwardly extending flange at the outer upper edge, a clamp having an upper flange in opposed relation to said front plate flange and a longitudinal slot, and a screw extending through said slot for adjustably securing said clamp to said plate, said plates being provided with a threaded hole for receiving said screw and said plates being welded to each other and to said bar.
4. The improvement defined in claim 3, wherein the rear plate of said second fixture extends to said bar, said bar thereby forming a portion of the rear of said socket and said bar being welded to said front plate of said second fixture.
5. The improvement defined in claim 3, wherein said bar is generally flat and is provided with a tapering ridge.
6. A fixture for curtain and drape bars, rods and the like, said fixture and a complementary fixture being adapted to be installed at opposite sides of a window or the like, comprising at least two plates attached together, in overlying relation, said plates forming, in upright position, an upright socket for receiving a bar-like member; and means for receiving a bracket or the like and removably attaching the same to said fixture.
7. A fixture as defined in claim 6, wherein said plates are attached together by welding.
8. A fixture as defined in claim 6, wherein said socket is provided by an offset portion of one of said plates.

9. The combination of a fixture, as defined in claim 6, and an angular member having a substantially co-planar flange extending into said socket of said fixture, the outer end of said member being thereby disposed laterally of said fixture; and an auxiliary fixture having an upright socket and means for removably attaching a bracket or the like thereto, said auxiliary fixture being attached to the outer end of said angular member.

10. The combination of a fixture, as defined in claim 6, and an auxiliary element including an arm having a flange extending into said socket of said fixture, said arm thereby extending forwardly from said fixture; and said arm being provided with means for supporting a rod for a drape, curtain or the like.

11. A fixture for curtain and drape bars, rods and the like, said fixture and a complementary fixture being adapted to be installed at opposite sides of a window or the like, comprising at least two plates attached together, in overlying relation, said plates forming, in upright position, an upright socket for receiving a bar-like member; one of said plates being provided with a flange extending outwardly therefrom and then in spaced, generally parallel relation to said plates; and a clamp attached to said plates and having a flange disposed in opposed relation to said plate flange.

12. A fixture as defined in claim 11, wherein said clamp is provided with a longitudinal slot; and a screw extending through said slot and said plates, said plates being provided with a threaded hole for said screw.

13. A fixture as defined in claim 11, wherein said socket is provided by an offset portion of one of said plates and said plate flange is disposed at the upper end of said plate having said offset socket portion and alongside said offset portion.

14. A fixture as defined in claim 11, wherein said plates are provided with longitudinally spaced holes at the side opposite said flange for attachment to a wall or the like.

15. An auxiliary element for a fixture having an up-

right socket therein, comprising an arm adapted to extend horizontally from said fixture and having a rear flange adapted to extend downwardly into said fixture socket; said arm being formed from flat stock and provided with a well for receiving a bar, rod or the like, said well having an open top, a horizontal bottom and generally vertical front and rear sides; said arm having at its outer end a box formed by said front side of said well, a horizontal top, a generally vertical end and a horizontal bottom extending back to said well, said box bottom and top being provided with aligned holes for receiving an angular end of a generally horizontal rod which is thereby swingable about said arm box, said well and said box being formed from a continuous strip from which said arm is formed.

16. An auxiliary element for a fixture having an upright socket therein, comprising a bar adapted to extend laterally from the upper edge of said fixture, said bar having an offset inner end spot welded to a flange bar adapted to extend downwardly in said fixture socket and the outer end of said bar being attached to a second fixture including front and rear plates with said front plate having a longitudinal offset portion in the center and a downwardly extending flange at the outer upper edge, a clamp having an upper flange in opposed relation to said front plate flange and a longitudinal slot, and a screw extending through said slot for adjustably securing said clamp to said plate, said plates being provided with a threaded hole for receiving said screw and said plates being welded to each other and to said bar.
